UNITED STATES PATENT OFFICE

1,988,502

CHAIN STITCH SEWING MACHINE

Michael McCann, St. Albans, Long Island, N. Y., assignor, by mesne assignments, to The Singer Manufacturing Company, Elizabethport, N. J., a corporation of New Jersey

Original application July 26, 1930, Serial No. 470,861. Divided and this application February 6, 1932, Serial No. 591,254

9 Claims. (CL 112—255)

This invention relates to sewing machines and more particularly to single thread or chain stitch machines, and has for its object to improve the control of the thread so as to prevent the formation of loose loops of thread in the finished work as frequently happens with this type of machine when used for sewing on buttons or wrapping wire or other strand materials or fabrics.

To this end a thread tension is interposed between the needle and the take-up which, however, is released at certain times. Such release is desirable particularly at the starting of a sewing operation to prevent the starting end of the thread from being drawn back out of the needle eye and at the end of the cycle to permit the thread to be drawn forwardly through the needle eye to leave sufficient length of thread extending therethrough for the start of a succeeding sewing operation.

20 This application covers subject matter divided out from my application Serial No. 470,861 filed July 26, 1930 for Sewing machines.

Referring to the accompanying drawings,

Figure 1 is a side elevation partly broken away of a sewing machine embodying this invention.

Figure 2 is a horizontal section on line 2—2 of Figure 1.

Figure 3 is a front end elevation of the machine in position to start the stitching cycle.

Figure 4 is a view to a larger scale similar to a portion of Figure 2 and showing the thread tension in operative condition.

Figure 5 is a detail section on line 5—5 of Figure 3 but showing the tension released.

Figure 6 is a detail section on line 6—6 of Figure 5.

Figure 7 is a fragmentary perspective of the tension and release mechanism.

Figure 8 is a detail section on line 8—8 of Figure 1.

Referring to the drawings, at 1 is shown the base of a sewing machine of a well known type for securing buttons with a single thread chain stitch, having a post 2 upstanding from its rear end merging with a forwardly extending arm 3 having a sewing head 4 at its forward end. At 5 is indicated a needle bar to the lower end of which a needle 6 having an eye 7 is secured. The needle bar is mounted for axial and lateral motion relative to the work. The axial motion is produced in any usual or suitable manner. As shown the relative lateral motion is effected by lateral motion of the needle and is produced through a lever 15 adjustably fulcrumed at 16, the forward end of this lever having a sleeve 17

through which the needle bar is slidably mounted. The rear end of the lever 15 is provided with a cam follower 14 riding in a cam groove 18 (see Figure 2) in a cam 19 fixed to a vertical shaft 20.

Beneath the needle bar the base 1 is provided with a work table 25 beneath which is positioned a looper such as 26 carried by a looper shaft 27. The looper is driven in suitable timed relation to and by the main shaft 10 by any suitable means as is well known in the art.

Beneath the arm 2 is positioned a work holder shown generally at 30. This work holder as shown is formed to engage wires which it is desired to wrap with thread but it might be a button clamp or other device if desired. A carrier bar 33 to the forward end of which the work holder is secured is hinged on a horizontal pintle 47 at its rear end so that the holder may be raised from the work table. It is normally held pressed toward the work table as by a spring pressed plunger 56 in a well known manner. It may be raised from the work to break the thread after the last stitch of a sewing operation to release the work as by the rocking of a rock shaft 70 (see Figure 3) to

which is fixed an arm 71 connected to the work holder as by means of a chain 72. An arm 75 fixed to the rock shaft may be connected to an actuating means such as a treadle (not shown) through a link 74. To the forward end of the rock shaft 70 may be secured an arm 131 provided with a thread retainer 130 for engaging the starting thread end prior to a stitching operation and holding it until the needle has engaged the thread with the work, whereupon the thread end is pulled out from the retainer as is more fully shown and claimed in my application for patent

Serial No. 591,253 filed February 6, 1932 for Sewing machine.

In order to prevent the formation of loose loops of thread, tension is applied, according to this invention, to the thread in the lead of the thread between the needle and the take-up. It is found that the descent of the needle from the beginning of its stroke has a tendency to bulge and pile up the thread between the needle eye and the work with the result that this bulge is often pierced by the needle point causing a loose stitch or damaged thread, or both. By positioning a stationary thread tension which thus does not move with the needle between the needle and the take-up, the thread is held tension-tight between the take-up and the work, allowing the needle eye to slide down the thread to the work without the possibility of bulging the thread. It is not desirable to apply this tension during the formation of the

first few stitches since tension applied at this time would be liable to pull the thread back through and unthread the needle as even when a retainer 130 is used during the first stitches the 5 thread end may be insufficiently securely caught.

At 190 in Figure 3 is shown a usual form of take-up mounted on the needle bar and from this, the thread as 191 passes downward through the tension 192 to the eye 7 of the needle. As shown 10 best in Figures 4, 5, and 6 this tension may comprise a bar 95 fixed as at 96 as by screws to the forward face of the sewing head 4 and having spring pressed against its forward face an element 97 which may be of sheet material having opposite edges flanged over as at 98 (see Figure 7) to engage opposite sides of the bar 95. At 99 may be placed notches in these flanges to form a thread guide. This element 97 may be pressed 15 against the forward face of the bar 95 and for this purpose there is shown a screw 100 extending through the element 97 and threaded into the bar 95 and surrounded by a coil spring 101. For the purpose of adjustment this screw 100 is shown as positioned within an opening 102 through the 20 front face of the head 4 so that it may be accessible to a screw driver for adjusting the extent of its engagement in the bar 95 and thus the pressure of the spring 101 on the element 97.

For the purpose of releasing the tension automatically during the first few stitches until the 25 starting thread end is sufficiently secured and at the end of the stitching cycle the following means may be provided. Fixed as by a screw 105 to the rear face of the bar 95 is a cam element 106 having an inclined cam face 107 and at its free end a forwardly extending portion 108 projecting through an opening through the bar 95 and into engagement with the rear face of the tension element 97. This member 106 may be formed 30 of sheet material and the portion 108 thereof may be formed by cutting and striking forwardly a portion thereof. By springing this cam member forwardly it is evident that the element 97 will be pressed away from the bar 95, thus relieving 35 the tension on the thread. This may be done by means of an arm 110 fixed to a rock shaft 111 journaled in the upper portion of the arm 3 and having at its rear end a cam arm 112 which may be engaged at the beginning and end of the 40 stitching operation by a cam projection 113 on the top face of the cam 19. The rock shaft 111 is normally held in such angular position that the arm 112 is depressed and the arm 110 retracted from engagement with the tension release member 106 as by means of a coil torsion 45 spring 114 shown in Figure 1. When the stitching cycle is about to stop the cam projection 113 rides beneath the arm 112, rocking this arm and moving the arm 110 over into tension-releasing 50 position shown in Figure 5.

On the start of a succeeding sewing operation the tension is held released until the projection 55 113 rides from under the arm 112, whereupon the tension is resumed. The free end of the tension element 97 is preferably bent forwardly as at 120 to facilitate placing the thread in position between it and the bar 95.

From the foregoing description of an embodiment 60 of this invention it should be evident to those skilled in the art that various changes and modifications might be made without departing from the spirit or scope of this invention as defined by the appended claims.

I claim:

1. In a sewing machine, sewing instrumentalities including a needle and a take-up, a thread tension between said needle and take-up and with respect to which said needle moves, and means automatically releasing said tension during a predetermined portion of the stitching operation. 5

2. In a sewing machine, sewing instrumentalities including a needle and a take-up, a thread tension between said needle and take-up and with respect to which said needle moves, and means automatically releasing said tension during a predetermined initial portion of the stitching 10 operation. 10

3. In a sewing machine, sewing instrumentalities including a needle and a take-up, a thread tension between said needle and take-up and with respect to which said needle moves, and means automatically releasing said tension during the formation of the first few stitches of a stitching 15 operation. 15

4. In a sewing machine, sewing instrumentalities including a needle and a take-up, a thread tension between said needle and take-up, means including a cam for vibrating said needle laterally between successive stitches, and means including an element of said cam for releasing said thread tension during a predetermined number 20 of stitches. 25

5. A thread tension comprising a bar, an element spring-pressed toward one face of said bar to grip a thread therebetween, and a cam member on the opposite face of said bar having a portion extended through an opening through said bar into engagement with said element and actuatable to press said element away from said bar to release the thread. 30

6. In a sewing machine, sewing instrumentalities including a needle and a take-up, a thread tension between said needle and take-up, means for grasping the thread end at the start of a sewing operation, and means for holding said tension inoperative while said thread end is being held by said grasping means. 40

7. In a sewing machine, sewing instrumentalities including a needle and a take-up, and a stationary thread tension between the needle and the take-up in the lead of the thread holding the thread under tension during a needle stroke between the take-up and the work whereby the needle eye may slide along the thread to the work without bulging the thread. 45

8. In a sewing machine, sewing instrumentalities including a needle and a take-up, a stationary thread tension between the needle and the take-up in the lead of the thread holding the thread under tension during a needle stroke between the take-up and the work whereby the needle eye may slide along the thread to the work without bulging the thread, and automatic means causing said tension to be inoperative at predetermined times. 55

9. In a sewing machine, sewing instrumentalities including a needle and a take-up, a stationary thread tension between the needle and the take-up in the lead of the thread holding the thread under tension during a needle stroke between the take-up and the work whereby the needle eye may slide along the thread to the work without bulging the thread, and automatic means causing said tension to be inoperative at the end of and at the start of machine operation. 65

MICHAEL McCANN,
